UNITED STATES PATENT OFFICE

WALTER L. UNDERWOOD AND CECIL F. STONE, OF GLENDALE, CALIFORNIA

CLEAR VISION TUBE FOR PNEUMATIC SYSTEMS

Application filed January 28, 1932. Serial No. 589,474.

This invention relates to a tube for use with a pneumatic carrier system, the general object of the invention being to provide the tube with a transparent outer part for covering the sales slip or other message carrying slip so that the indicia on the slip can be easily and quickly read and thus facilitate the handling of sales in department stores or the like, and the invention also prevents the slips being accidentally left in the tube or the slips being crumpled or wrinkled or otherwise damaged to make the indicia thereon hard to read.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings, wherein like characters denote like or corresponding parts throughout the several views, and in which:

Figure 1 is an elevation of the improved tube.

Fig. 2 is a view showing the parts in a different position to show the slots for receiving a part of the sales slip.

Fig. 3 is a view similar to Fig. 2, but showing the parts in a position to show the registering openings for permitting money or the like to be placed in the tube.

Fig. 4 is a section on line 4—4 of Fig. 1.

Fig. 5 is a view of the outer or transparent part with the end portions attached thereto.

Fig. 6 is a view of the inner or metal tube which fits in part connected thereto.

Fig. 7 is an elevation of the entire device showing the parts in position where one slot engages another.

Fig. 8 is a section on line 8—8 of Fig. 2.

Fig. 9 is a section on line 9—9 of Fig. 3.

Fig. 10 is a section on line 10—10 of Fig. 1.

In these drawings, the numeral 1 indicates the inner tube formed of metal and having an opening 2 therein and the numeral 3 indicates the transparent outer tube which is formed with the opening 4 which is formed with the narrow extensions 4' at its ends. The inner tube 1 is formed with a hollow rib 5 which

is extended inwardly and formed with a slot which opens out through the side of the tube for receiving a part of a sales slip A or other sheet shown in dotted lines in Fig. 8. This rib also acts as reinforcing means for the metal tube and the extensions 4' of the opening 4 covers this slot when the parts are in a certain position, and as shown in Fig. 3 so as to facilitate the entrance of a part of the slip in the slot.

The openings 2 and 4 are of substantially the same size so that they will permit money or the like to be placed in or removed from the device when they are in registering position or nearly so, as shown in Fig. 3. The ends of the inner tube 1 are closed as shown in Fig. 4, and caps 6 and 7 fit over the ends of both tubes and the tubes are held slightly spaced apart by the end members 8 so that the slip or sheet A can fit between them and after a part of the slip is placed in the slot with the parts in position as shown in Fig. 2, a turning movement of one tube relative to the other will wind the slip on the inner tube and under the outer tube, and as this outer tube is formed of transparent material the printing or other matter on the slip will be visible therethrough.

End pieces 9, formed of felt or the like, to snugly fit the conduits of the pneumatic system, are connected to the caps 6 and 7 by the bolts or screws 10 and one of these end pieces is connected to one end of the inner tube 1 by the bolts as shown in Fig. 4, but the other end is simply connected to the other end of the tube by a central bolt 11 so that said other end piece is pivotally connected to said end of the inner tube.

The corresponding end of the outer tube B is connected to the last-mentioned end piece or to the cap 6, so that it will rotate when this end piece is rotated so that by holding one of the end pieces stationary and turning the other, one piece will rotate relative to the other though it will of course be understood that by rotating the end pieces in opposite directions, the tubes will be turned in opposite directions. The end pieces are formed with the recesses 12 for receiving the

100

outer ends of the bolts and the washers 14 through which the bolts pass.

A stop 15 is formed on the cap 7 and a stop 16 is formed on the adjacent end of the outer tube 3, and these stops will engage each other when the tubes are in a position closing the openings as shown in Fig. 7, and these stops prevent the parts being turned so far as to wind the slip so far that its ends will be entirely covered which will make it difficult to remove the slip.

Fig. 10 shows the parts with the stops in engagement and one end of the slip exposed.

A leather washer 17 fits between one of the end pieces and the cap 6 for increasing the suction action when the tube is placed in the conduit.

Thus it will be seen that it is simply necessary to turn the parts to the positions they occupy in Fig. 2 and then insert part of the sales slip or other message carrying sheet into the slot and then by turning the parts, the slip will be wrapped around the inner tube and under the outer tube as shown in Fig. 10 and if money or other matter is to be transported by the device, the money or other object is placed in the device when the openings come opposite each other as shown in Fig. 3. As will be seen from Fig. 10, when the stops 15 and 16 are in engagement with each other, the openings will be out of register, so that the money will be held in the device and a slip will be placed between the two tubes and one end partly projected.

The device is then placed in a conduit in the usual manner, but when it reaches the place for which it is meant, the operator at this place can readily read the matter on the slip so that no time is lost in sending the tube to the person for which it is intended.

The felt end pieces act as guides as well as bumpers, as the carrier leaves the pneumatic tube and falls in the receiver and if desired arrows may be placed on the flanges of the caps 6 and 7 to indicate the direction of turning of the parts to wind the message into the tube carrier.

This device also enables the operators to more quickly see the signatures of the sales checks and should they be looking for fraudulent purchasers the detectives could stand at the place where the tubes come through and quickly glance at the handwriting and check to see if there is any handwriting they are looking for and they could quickly go to the department from which the tube was sent before the purchaser becomes nervous due to any delay.

As it is now the detectives must wait until the tubes are relayed to the authorizers and sort through the duplicate O. K.'d sales checks going to one girl and then another looking at the handwriting. By the time it is found enough time has elapsed to allow the purchaser to receive the O. K.'d stub and

be on her way before the arrival of the detective in the department.

It is thought from the foregoing description that the advantages and novel features of the invention will be readily apparent.

It is to be understood that changes may be made in the construction and in the combination and arrangement of the several parts provided that such changes fall within the scope of the appended claims.

Having thus described our invention, what we claim as new is:—

1. A carrier tube for a pneumatic tube system comprising inner and outer cylinders having openings therein, the outer cylinder being formed of transparent material, rings placed between the end portions of the cylinders for slightly spacing them apart, means for rotating one cylinder in relation to the other, and means for attaching a part of a sales slip or the like to the inner cylinder whereby the slip will be wrapped on the inner cylinder and under the outer cylinder, when one cylinder is rotated with respect to the other.

2. A carrier tube for a pneumatic tube system comprising inner and outer cylinders having openings therein, the outer cylinder being formed of transparent material, means for rotating one cylinder in relation to the other, means for attaching a part of a sales slip or the like to the inner cylinder whereby the slip will be wrapped on the inner cylinder and under the outer cylinder, when one cylinder is rotated with respect to the other, such means comprising an internal rib formed on the inner cylinder and providing a slot extending outwardly for receiving a part of the slip.

3. A carrier tube for a pneumatic tube system comprising inner and outer cylinders having openings therein for permitting access into the inner cylinder, the outer cylinder being formed of transparent material, end pieces, one of which is connected to the inner cylinder and the other to the outer cylinder, said end pieces being formed of felt or the like and of greater diameter than the cylinders, spacer rings placed between the end portions of the cylinders for slightly spacing them apart, and means on the inner cylinder for detachably receiving an end of a slip or sheet whereby said slip or sheet will be wrapped around the inner cylinder under the outer cylinder when one cylinder is rotating with respect to the other.

4. A carrier tube for a pneumatic tube system comprising inner and outer cylinders having openings therein for permitting access into the inner cylinder, the outer cylinder being formed of transparent material, end pieces, one of which is connected to the inner cylinder and the other to the outer cylinder, said end pieces being formed of felt or the like and of greater diameter than the

cylinders, an internal rib formed on the inner cylinder and providing an outwardly opening slot for receiving a part of a sales slip and the ends of the opening in the outer 5 cylinder being extended, stop means for limiting rotary movement of the cylinders and a washer located on the inner end of one of the end pieces.

In testimony whereof we affix our signatures.

CECIL F. STONE.
WALTER L. UNDERWOOD.
